DESIGN FOR A HANDBAG

Gustav G. Rona, Trenton, N. J., assignor to King Innovations, Incorporated, New York, N. Y., a corporation of New York

Application April 4, 1938, Serial No. 76,268

Term of patent 7 years

To all whom it may concern:

Be it known that I, Gustav G. Rona, a citizen of the United States, residing at Trenton, county of Mercer, State of New Jersey, have invented a new, original, and ornamental Design for a Handbag, of which the following is a specification, reference being had to the accompanying drawing, forming part thereof.

Figure 1 is a front view of a handbag showing my new design.

Figure 2 is an end view of the handbag shown in Figure 1.

The cross hatching on the handle and on the left and right triangular side panels is continued throughout these portions to indicate a color appearance which contrasts with the vertical stripe between the two triangular side panels and the arc shaped lower portion. The other or rear side of the bag shown in Figure 1 is substantially plain.

I claim:

The ornamental design for a handbag, substantially as shown and described.

GUSTAV G. RONA.
